UNITED STATES PATENT OFFICE.

WILLIAM R. STANDEN, OF NEW YORK, N. Y.

DRAWERS.

SPECIFICATION forming part of Letters Patent No. 349,910, dated September 28, 1886.

Application filed April 29, 1886. Serial No. 200,576. (No model.)

To all whom it may concern:

Be it known that I, WILLIAM R. STANDEN, of the city, county, and State of New York, have invented new and Improved Drawers, of which the following is a full, clear, and exact description.

The object of my invention is to so shape and unite the various parts which enter into the construction of the waistband of a pair of drawers that the band will act as a support to the spine, and be adjusted to proper size from the front instead of from the back of the drawers; and to the ends named the invention consists of a waistband for drawers wherein the 10 lining and the main sections of the band are cut, so that when made up the band, when adjusted to position, will conform to the general contour of the body, the back of the band being permanently closed, while the proper 15 adjustment as to size is obtained by means of buckles and straps that are secured to the forward meeting ends of the band.

Reference is to be had to the accompanying drawings, forming a part of this specification, 20 in which similar figures of reference indicate corresponding parts in all the figures.

Figure 1 is a diagram representing the form to which the main portions of the band are cut. Fig. 2 is a view of the partially-completed band, representing the parts as stitched together, a portion of one of the main pieces being, however, broken away in order that the arrangement of the interlining may be more clearly represented. Fig. 3 is a view of 30 the band as it appears when the meeting edges are united by the straps and buckles, a portion only of the body of the drawers being shown; and Fig. 4 represents the drawers as applied to the person.

40 The drawers-band forming the subject-matter of this application is made up of four main strips or pieces, which are slightly wider at one end than they are at the other, the wider end of each strip being cut upon an inward curve for a purpose to be presently explained.

In Fig. 1 the form to which the several strips or pieces are cut is very fully illustrated, 45 10 being the strips proper, 2 being the narrow end of the strip, and 3 the broad end, 50 which is formed with an inward curve, 4. As above stated, four of these strips or pieces 10

are employed in the construction of the drawers band, two pieces being employed for the outside of the band while two are for the lining, an intermediate lining being interposed 55 between the outside of the band and its lining. This intermediate lining, 11, which is arranged as shown in Fig. 2, consists of a strip of slightly-elastic canvas, 6, and a strip of linen, 5, which, as will be understood, is inelastic, the 60 idea of this construction being to allow a certain amount of elasticity at the back of the band, but to so form the sides of the band that they will not stretch or give, the strain coming upon the centers of the strips 6, the 65 edges of which are cut on a slight bias in order that they may spring out over the hips. After the parts are arranged as indicated they are basted to place, as shown in Fig. 2, and to the ends 2 of the outer strips 10 there are basted 70 strips 7 and 8, the strips 7 being employed for the purpose of attaching buckles 9, while the strips 8 are formed into straps adapted to engage with the said buckles, each set of strips being overlapped by facing strips 12. After 75 the various parts have been adjusted and basted to place the rear portion of the belt is quilted, and a pad, 20, is formed, which fits against and supports the base of the spine, as shown in Fig. 4, the body of the drawers being inserted and held in place as indicated in 80 Figs. 3 and 4. By forming the ends 3 of the strips 10 as shown at 4, it will be understood that when the parts are united the band will have substantially the shape illustrated in 85 Fig. 4, and will conform to the contour of the small of the back, thus acting as a brace to the spine, as well as an effectual shield from the injurious effects of sudden changes of temperature or heavy drafts.

90 By placing the adjusting device—that is, the straps and buckles—in front, instead of behind, I arrange for the quick and accurate adjustment of the garment to the size of the wearer, and at the same time obtain a band which is 95 closed behind, so that it will fit snugly against the body at the base of the spine, there to serve the purpose hereinbefore set forth; hence it will be seen that drawers constructed in accordance with the terms of my invention combine all the advantages arising from the use of 100 a separate waistband without subjecting the

wearer to the inconvenience of buttoning and adjusting a separate garment or appliance.

Having thus fully described my invention, what I claim as new, and desire to secure by 5 Letters Patent, is—

1. Drawers provided with a waistband permanently closed at the back and provided with buckles and straps on its free ends, the said back portion being padded and convex 10 transversely to conform to the contour of the small of the back, substantially as herein shown and described.

2. As a new article of manufacture, drawers provided with a waistband made up of

strips or pieces, the permanently-united ends 15 of which are cut with an inward curve, while the forward ends are provided with straps and buckles, substantially as described.

3. As a new article of manufacture, drawers provided with a waistband consisting of 20 four strips, 10, formed with ends 3, cut with a curve, 4, intermediate lining, 11, buckles 9, and straps 8, substantially as described.

WILLIAM R. STANDEN.
